UNITED STATES PATENT OFFICE.

MAURITZ C. INDAHL, OF PHILADELPHIA, PENNSYLVANIA, ASSIGNOR TO LANSTON MONOTYPE MACHINE COMPANY, OF PHILADELPHIA, PENNSYLVANIA, A CORPORATION OF VIRGINIA.

TYPOGRAPHIC CASTING MACHINE.

Application filed December 4, 1923. Serial No. 678,544.

To all whom it may concern:

Be it known that I, MAURITZ C. INDAHL, a citizen of the United States, and a resident of Philadelphia, county of Philadelphia, 5 State of Pennsylvania, have invented certain new and useful Improvements in Typographic Casting Machines; and I do hereby declare the following to be a full, clear, and exact description of the same, reference being had to the accompanying drawings, forming part of this specification, and to the characters of reference marked thereon.

This invention relates to typographic casting machines and has for its principal object 15 the construction of mold mechanism for the production of typographic elements particularly in the form of fused strip, and, as illustrated, fused strip of the I-shaped or rail-shaped kind. Its objects furthermore include a nozzle structure having a plurality of inlet branches: and also include a nozzle structure with an inlet passage and provided with a vent opening of relatively small size through which air in the mold cavity 20 is adapted to be discharged by the molten metal injected into the mold cavity. Other objects will be hereinafter pointed out or will otherwise appear in connection with the following description of the particular embodiment of the invention which is shown 25 in the accompanying drawings in which,

Fig. 1 is a plan view of a mold constructed in accordance with the invention.

Fig. 2 is a front elevation thereof.

Fig. 3 is an end elevation, parts being broken away to show in section the friction plunger.

Fig. 4 is a vertical section on approximately line 4—4 of Fig. 1, and showing the melting pot and nozzle, and in a diagrammatic form the pump mechanism.

Fig. 5 is a vertical cross section on approximately line 5—5 of Fig. 1.

Fig. 6 is an enlarged section showing the mold cavity and nozzle, the direction of flow of metal in the mold cavity being illustrated by dotted arrows.

Fig. 7 is a plan view of the nozzle.

Fig. 8 is a vertical section through the vent of the nozzle.

Fig. 9 is a perspective view of the plug employed in producing the vent, and

Fig. 10 is a perspective view of the nozzle.

The mold illustrated is adapted to produce strip material of a form capable of being employed in a multigraph or like machine for printing purposes. The cross section of this strip is generally I-shaped or rail-shaped, and the strip may be conveniently termed rail-type strip material. The 55 mold employs as its operating principle the fusion of successive casts such as is set forth, for example, in United States Letters Patent No. 1,222,415, dated April 10, 1917. It is to be used in connection with a suitable casting machine in which a pump mechanism injects molten type metal or the like into the mold cavity through a nozzle; the nozzle being retracted after each cast; one end of this cavity is closed by the rear face of the 60 section previously cast, and the opposite end is formed by the end of the mold blade, which, after the metal has been injected into the mold cavity and cooled into a solid therein, pushes said section which has been fused 65 to the previous section, in order to eject from the mold the finished cast strip; after the ejection by the mold blade, the latter is retracted to form a mold cavity, and the 70 process is repeated, it being understood that the timing of the various parts of the machine, including movements of the pump, the nozzle and the mold blade, is such as to work harmoniously to the end that a suitable 75 product is produced. A machine constructed 80 to operate in conjunction with the mold illustrated may be similar to that basically shown and described in United States Letters Patent No. 625,998, May 30, 1899.

The mold illustrated comprises a base 85 member secured to and supported on the machine frame 11. This base member has a flat central base portion 12 and two upstanding longitudinal portions 13 and 14 forming a channel between them. The machine base 11 is provided with an opening 15, and the base 12 of the channel-shaped base member is also provided with an opening 16 in registry with the opening 15 of the machine frame, these openings being for 90 95 100

the purpose of allowing the nozzle, to be described later, to seat upon the nozzle plate 17 located within the channel of the base member and provided with a conical aperture 18 in registry with the holes 15 and 16, the aperture 18 forming a conical seat for the nozzle. The nozzle plate is removable from the base plate and is supported thereon within the channel therein. Above the nozzle plate 17 are the front and rear type blocks 19 and 20, their proximate faces being separated to accommodate between them the mold blade 21. In the form shown, these proximate faces of the type blocks are rabbeted so that when they are in position the space between them is of a cross section corresponding with that of the rail-type strip material desired to be produced. The mold blade is of course of a similar cross section and has a sliding fit between the proximate faces of the type blocks. The type blocks, the nozzle plate and the base member are screwed together by screws 22 extending from below and shown in dotted lines in several of the figures. These screws extend through holes in the base member 12 and the nozzle plate 17 and screw into the type blocks, the holes being slightly larger than the screws so that the type blocks may be adjusted laterally relatively to each other to produce a proper sliding fit of the mold blade. This adjustment is accomplished by the plungers 23, shown in dotted lines in Fig. 1, which may be moved by turning their screwheads 24 screwthreaded in the upstanding portion 13 of the base member. The ends of the plungers are in the horizontal plane of the type blocks 19 and 20, and it is obvious that by turning the screws 24, the type block 19 may be adjustably moved with relation to the type block 20. The nozzle plate 17 and type blocks 19 and 20 are of approximately the same length as the mold base, and the type blocks are of a height corresponding with the height of the body of the material to be produced.

Located upon the type blocks and in the channel of the base member are the front and rear matrix blocks 25 and 26 respectively. They are secured by screws 25' extending upwardly through the base 12, the nozzle plate 17 and the type blocks 19. The matrix blocks are provided above the nozzle seat 18 in their meeting faces with a cut-out portion to produce a matrix well 27 in which a matrix 28 is adapted to be positioned and guided. The blocks are also provided centrally with upstanding lugs 29 and 30 undercut so as to cooperate with the hook portions of the clamp 31, this clamp being provided with a screw 32 extending vertically through the clamp with its end in contact with the upper surface of the matrix. When the screw 32 is manually operated,

the matrix 28 may be forced under pressure against the two type blocks which it spans directly above the nozzle opening. It is to be readily understood however that this matrix may, if desired, be moved up and down, the walls of the well 27 serving as a guide therefor, if it is desired to produce a product having cast thereon a border or design requiring the movement of the matrix.

The moving of the matrix may be accomplished in any well-known fashion such as is shown, for example, in United States Letters Patent No. 1,465,272, dated August 21, 1923. The matrix blocks 25 and 26 abut along their meeting surfaces except where the well 27 has been provided and where they are cut away to accommodate the mold blade carrier. They are fastened together by means of the screws 33 and 34, the former screw passes through the lugs 35 on the bottom of the matrix blocks 25 and 26 and the screw 34 passes through lugs 36 on the top of the matrix blocks. Suitable separating plates 36' may be provided between the lugs so as to separate the blocks a sufficient amount to provide between them a sliding fit for the mold blade carrier 37. This carrier is supported on the shelf 38 screwed to the matrix block 25 by screws 39, and on the lower plate 36'. The upper surface of the blade carrier 37 is guided by the shelf 40, fastened by screws 41 to the block 25, and by the upper plate 36'. The mold blade carrier 37 is provided with a hole 42 into which the usual operating mechanism for the mold blade is adapted to project and the rear matrix block 26 is suitably cut away to provide for this mechanism at any position thereof. The mold blade carrier is also provided with a slot 43 into which projects a stop 44 fastened by screws 45 to the end of the matrix block 25, this stop being provided to determine the position of the mold blade at the forward end of its stroke at which position the rearward end of the slot 43 comes against the stop 44. The mold blade carrier 37 is cut away at its forward lower corner and a square aperture is provided between the hole 42 and this cut away portion, said aperture extending into said portion and being of such dimension as to accommodate lug 46 provided on the rear end of the mold blade 21 and extending upwardly therefrom, the blade 21 extending into and forward of said cut away corner of the holder. The blade and holder may be readily assembled with the lug 46 in position to enter the square aperture. When assembled, the walls of the square aperture will transmit reciprocating motion from the mold blade holder 37 to the mold blade 21. The mold blade 21 is shaped of course to correspond with the cross section of the material to be produced and in this particular case is, as shown, of rail-shaped cross

section. It is to be observed that the mold blade holder 37 and the lug 46 of the mold blade are guided by the matrix blocks 25 and 26, which blocks also position and guide the matrix.

The mold is cooled by a system of waterways 47 which extend through the base of the mold and through the nozzle plate, type blocks and matrix blocks in such a way as to cause cooling water to flow in proximity to the casting cavity. Entrance and exit of the water is at the points 48 and 49 respectively. These entrance and exit ports register with similar ports in the base 11 of the machine in the usual manner so that when a mold is secured to the base of the machine, as by screws 50, the ports 48 and 49 will be positioned and bound against the machine base so that water may be caused to flow, without leakage between the mold and the machine.

The mold base is provided with a friction mechanism comprising a channel block 51 screwed to the end of the mold base by screws 52. Within the channel of this block is an abutment block 53 secured to the block 51 by screws 54, the forward face of this abutment being shaped to contact with the rear face of the strip material as it issues from the mold under the ejecting action of the mold blade. In the form shown, the front face 53' of the block 53 is shaped to contact with the upper and lower shelves of the rail-shaped product. The front portion of the block 51 is provided with a bore for the accommodation of the plunger 55, which is hollow for the reception of the coil spring 56, one end of which exerts pressure on the plunger to force it rearwardly toward the abutment 53, and the other end of which is in contact with the screw plug 57 screwthreaded into the block 51. By screwing the plug 57 one way or the other, the tension of the spring may be varied and the force with which the plunger 55 is pressed against the front face of the strip material may be thereby regulated. The rear wall 58 of the plunger 55 is shaped so as to contact with the front face of the strip material being produced. In the form shown this face 58 is formed similarly to the face 53' of the abutment block 53. The plunger 55 is also provided with a horizontally extending lug 59 which extends under the base of the material being produced and is adapted to contact with the block 53 in case there is no strip material between the plunger and the abutment. The abutment and the lug 59 therefore act to form a stop to prevent undue movement of the plunger.

It has been found desirable to employ a nozzle of novel construction in connection with a rail-type mold, such mold having a relatively long stroke as compared with the height of the product produced. In other

words, the height being less than usual, the length of stroke may be longer than usual in order that approximately the same capacity of pump operation may be employed, although the ordinary nozzle, such as shown in Patent 1,222,415, may be employed with a short stroke operation. It is desirable, when longer strokes are employed and particularly when the casting is performed at high speed, to employ a special nozzle which is so constructed that proper fusion is obtained for the joining together of the sections of the product, and at the same time a quick filling of the mold is accomplished. This nozzle 60, as shown, is provided with a central bore 61 which leads from the lower end 62 of the nozzle which is exteriorly screwthreaded, to a point in proximity to the mold cavity. Branch conduits 63 and 64 connect the upper end of the nozzle with the conduit 61. The nozzle, is, as usual in the form of a truncated cone near its upper end, the conical walls 65 of which seat against the conical seat 18 in the nozzle plate. At the upper end of the nozzle above the conical portion 65 is a horizontal flat area 66 through which the inlets of the conduits 63 and 64 discharge directly into the mold cavity formed by the type blocks 19 and 20, the matrix 28, the mold blade 21 and the rear end wall of the material previously cast. The branches 63 and 64 extend angularly from the central bore 61 and the angles are so chosen that the metal issuing from the channel 63 will wash directly against the rear wall of the previously cast section, while the angle of the branch 64 is such as to direct the metal flowing through it into the rearmost portions of the cavity. In order that the branches may be positioned correctly, the nozzle end 62 is screwthreaded into the pump body 67 and is, when properly positioned, locked by the lock nut 68 in an obvious manner. The pump body 67 is of course provided with a bore or channel, one end of which communicates with the bore 61 in the nozzle and the other end of which connects with the pump mechanism 69 diagrammatically illustrated in Fig. 4. The flat upper end 66 of the nozzle which is provided with the inlets 63 and 64 is also provided with a vent outlet port 70 which extends downwardly and angularly through the nozzle to a point 71 exteriorly of the nozzle and below the conical portion 65 thereof. This vent 70 is preferably formed, as shown particularly in Figs. 8 and 9, by boring a circular hole and plugging the upper end thereof by a plug 72 which is cylindrical to fit the hole but one side of which has been flattened at 73 (Fig. 9) so that when the plug is placed in the hole, there remains a minute segmental aperture.

It will be observed, particularly from an inspection of Fig. 6, that a stream of metal

injected into the mold cavity through the bore 61 of the nozzle is split up by the branch bores 63 and 64 so that part of the metal, that passing through the branch 63, 5 is directed to wash up against the wall of the previously cast product in order to cause fusion between the previously cast product and that portion being cast in the mold cavity. This metal may follow the direction 10 shown by the dotted arrows in Fig. 6. The other branch conduit 64 leads the metal angularly from the bore 61 and directs it to the rear end of the mold cavity, as shown also by dotted arrows. The metal which comes 15 into contact with the walls of the mold will of course quickly solidify and that portion which last solidifies will be in proximity to the nozzle itself, which, of course, is at all times hot enough so that the metal will not 20 freeze in its passages. It is of course understood that the nozzle is moved up and down in proper timing relation to the other movements of injecting metal into the mold and ejecting the product therefrom and that 25 when the nozzle is in its down position, it gains heat from the metal pot 74, a fragmentary showing of which is in Fig. 4, and that when the nozzle has seated against the mold it loses heat to the mold. The nozzle passages for the injection of metal are necessarily of sufficient size and capacity that the 30 metal does not solidify or freeze in said passages during the time that the nozzle is in contact with the mold.

35 The vent passage in the nozzle is located as to its mold cavity end, between the inlet fan-shaped conduits 63 and 64 and at a point where the metal in the mold cavity solidifies last. With such location of the vent coupled 40 with the proper angular positioning of the inlet branches 63 and 64, air which may be in the cavity is driven in such manner as is shown by the arrows in Fig. 6, so that it is forced out through the vent 70 and discharges exteriorly of the nozzle at the point 45 71 from which it emerges under the hydraulic pressure exerted by the pump. It may be that in addition to air, after the air has been expelled, some metal will escape through the vent 70; if so this metal is discharged in such a manner that it drops back 50 into the pot 74. The size of the opening 70 is relatively very small and may be termed minute, although its actual size may vary, 55 depending upon the quality and composition of the metal used, upon the temperature of the metal, its fluidity and other factors. In general however the vent may be described as relatively very small or minute, its size 60 being such that air will readily escape and possibly some metal also, provided the pump pressure is on and the metal is still relatively fluid; but the vent must be so small that even with some hydraulic pressure the vent 70 65 will freeze before very much metal has es-

caped. The freezing of this vent is momentary only because when the nozzle drops to its lower position the heat of the nozzle will immediately melt the metal frozen in the vent so that it will be ready to operate correctly the next time the nozzle is seated and the pump pressure applied. 70

In order to illustrate the capacity of the vent it may be stated that under certain operating conditions the main bore of the vent was measurable in a few hundredths of an inch so that its cross sectional area would be about one-thousandth of a square inch. When the plug 72 was put into place the segment opening left would have obviously an 75 area of about one-third of that of the main bore: so that the area for the discharge is thus reduced by the plug to only a few ten-thousandths of a square inch. This example is given not to limit the invention to the dimensions suggested so far as the vent is concerned because there are a variety of factors which would determine the size of the vent as previously suggested. It is given to show that the vent is in fact of extremely small 80 size; it must not be so large in capacity that metal will run out of the mold cavity after the latter has been filled and the metal therein has started to congeal, which escape of metal would produce a product having "bleeding feet"; and yet it must be of sufficient size that practically all the air in the cavity will be expelled under the hydraulic pressure of the molten metal during the 85 small period of time provided for producing 90 a cast section and that it will not become clogged by small particles of dross. 95

I claim:

1. In a typographic casting machine, the combination of a mold comprising cavity forming walls, one of said walls being provided with an inlet port, the walls of which port form a nozzle seat, a nozzle provided with a bore and pump mechanism for introducing molten metal under pressure through 105 said bore into said cavity, said nozzle being provided with a vent leading from said cavity to the exterior of the nozzle and being of such minute size as to prevent exit of metal except when under pressure exerted by the 110 pump mechanism. 115

2. A nozzle for a typographic casting machine comprising a screwthreaded end for attachment to a pump mechanism, its opposite end being in the form of a truncated 120 cone to seat against the nozzle seat of a typographic mold, said nozzle being provided with a conduit extending from said screwthreaded end to the opposite or mold end of the nozzle, said nozzle being also provided 125 with a vent leading from said mold end of the nozzle to the exterior thereof and being of such minute size as to prevent exit of metal except when under pressure exerted by the pump mechanism. 130

3. In a typographic casting machine, the combination of a mold comprising cavity-forming walls, one of said walls being provided with an inlet port, the walls of which 5 port form a nozzle seat, a nozzle, and means for introducing molten metal into the cavity through the nozzle, said nozzle being provided with an axial conduit terminating at its inner end in a plurality of branches for 10 directing the metal angularly into different parts of the mold cavity, and being also provided with a vent leading from said cavity to the exterior of the nozzle, said vent being of such minute size as to prevent exit of 15 metal except when under pressure exerted by the pump mechanism.

4. A nozzle for a typographic casting machine comprising a screwthreaded end for attachment to a pump mechanism, its opposite 20 end being in the form of a truncated cone to seat against the nozzle seat of a typographic mold, said nozzle being provided with an axial conduit extending from said screwthreaded end into proximity to the opposite or mold end of the nozzle, and 25 branch conduits leading angularly from the axial conduit through the mold end of the nozzle, said branch conduits being in the same axial plane, said nozzle being also provided with a vent leading from the mold end 30 of the nozzle to the exterior thereof between the truncated cone seat portion and the screwthreaded end of the nozzle, said vent being of such minute size as to prevent exit 35 of metal except when under pressure exerted by the pump mechanism.

5. In a typographic casting machine, the combination of a mold comprising cavity-forming walls, one of said walls being provided with an inlet port, the walls of which 40 port form a nozzle seat, a nozzle, and pump mechanism for introducing molten metal into the cavity through the nozzle, the latter being provided with an axial conduit in 45 communication with the pump and extending into proximity to the mold cavity, and a plurality of fan-shaped branch conduits connecting said axial conduit with said cavity, the nozzle being also provided with 50 a vent leading from said cavity at a point between the inlets of said fan-shaped branch conduits to the exterior of the nozzle, said vent being of such minute size as to prevent exit of metal except when under pressure 55 exerted by the pump mechanism.

6. A typographic casting machine comprising cavity-forming mold walls, one of said walls being provided with a nozzle opening, a nozzle adapted to be seated in 60 said opening and provided with a passage-way through which molten metal may be introduced into the mold cavity, a vent being provided in said nozzle, leading from said cavity to the exterior of the nozzle, said vent

being of such minute size as to prevent exit 65 of metal except when under pressure exerted by the pump mechanism.

7. A typographic casting machine comprising cavity-forming mold walls, one of said walls being provided with a nozzle 70 opening, a nozzle adapted to be seated in said opening and provided with a central bore and a plurality of fan-shaped bores connecting said central bore with said cavity, a relatively small vent being provided in 75 the nozzle, leading from said cavity at a point between the inlets of said fan-shaped bores to the exterior of the nozzle.

8. A casting machine comprising a mold for producing fused strip material for printing forms and comprising a mold base, type blocks, a mold blade and a matrix, said base being provided with a nozzle opening, and in combination therewith a nozzle adapted 80 to be seated in said opening and provided with a central bore and two angular bores connecting said central bore with said cavity, one of said angular bores directing metal against the end wall of the last cast 85 section to produce fusion therewith and the other being directed to fill the mold quickly, a relatively small vent being provided in the nozzle, leading from the cavity at a point between the inlets of said two angular bores to the exterior of the nozzle. 90

9. A mold for typographic strip material comprising a base provided with an opening, a removable nozzle plate supported on said base and provided with a nozzle opening in registry with said opening in the 100 base, said nozzle opening having conical walls to form a nozzle seat, type blocks located above said nozzle plate, a mold blade between the blocks, and means for adjusting said blocks relatively to each other to provide a proper sliding fit for the mold blade. 105

10. A typographic casting machine comprising a pump and mold mechanism for producing printers' strip material and delivering it in finished condition, and in combination therewith, a friction device including an abutment contacting with one side of said finished strip material and a plunger contacting with the opposite side thereof, a spring for yieldably forcing said plunger 110 against the material, and means for controlling the contacting pressure of said plunger against the material whereby accidental movement of the material due to the hydraulic pressure produced by the pump is prevented. 115

11. A mold for typographic strip material comprising a base provided with a nozzle opening, type blocks mounted on said base, matrix blocks mounted on said type blocks, a matrix guided by said matrix blocks and adapted to seat upon said type blocks and a mold blade slidable between the type blocks 120

and having a forwardly extending end portion guided between said matrix blocks.

12. A mold for typographic strip material comprising a base provided with a nozzle opening, type blocks mounted on said base, matrix blocks mounted on said type blocks, a matrix guided by said matrix blocks and

adapted to seat upon said type blocks, a mold blade slidable between the type blocks and a mold blade holder slidably guided between said matrix blocks and detachably secured to said mold blade to cause reciprocation of the latter. 10

MAURITZ C. INDAHL.
